CLAIM

The ornamental design for a footwear, as shown and described.

DESCRIPTION

FIG. 1 is a front, top and right side perspective view of a footwear according to the new design;

FIG. 2 is a front side elevation view thereof;

FIG. 3 is a back side elevation view thereof;

FIG. 4 is a right side elevation view thereof;

FIG. 5 is a left side elevation view thereof; and,

FIG. 6 is a top plan view thereof.

The short broken lines on the claimed surface are stitching, which does form part of the claimed design. The other broken lines in the drawings show portions that form no part of the claimed design.
